B. SEAMAN

DISPLAY BOX

Filed August 6, 1925

Fig. 1.

The diagram shows a curved, segmented object, likely a mold or a part of a machine. It consists of three main segments, each labeled 15. The segments are separated by vertical lines labeled 16. The top edge of the segments is labeled 17. The bottom edge of the segments is labeled 18. The overall width of the object is labeled 23. The top edge of the segments is labeled 17. The top edge of the entire object is labeled 14. The left side of the object is labeled 13. The right side of the object is labeled 14. The figure is labeled Fig. 3. There is also a separate figure labeled Fig. 5, which shows a rectangular block with a curved top edge labeled 14 and a vertical line labeled 24.

-10 Inventor:
Barney Seaman.

F. V. Winters
Attorney

UNITED STATES PATENT OFFICE.

BARNEY SEAMAN, OF NEW YORK, N. Y.

DISPLAY BOX.

Application filed August 6, 1925. Serial No. 48,537.

To all whom it may concern:

Be it known that I, BARNEY SEAMAN, a citizen of the United States, residing at New York, county of Bronx, and State of New York, have invented certain new and useful Improvements in Display Boxes, of which the following is a specification.

This invention relates to improvements in display boxes for articles of merchandise.

10 The objects of the invention are:

First, to provide in an article of the class described a holder for the articles of merchandise which is adapted to display said articles in a similar position as worn by the 15 purchaser.

Second, to provide a display box having a plurality of holders therein, each holder being readily accessible for removal or replacement.

20 Third, to provide a display box capable of being exhibited in different positions and occupying but little space within or upon a showcase.

Fourth, to provide improved means for 25 retaining the holders within said display box.

Further objects and objects relating to details and economies of construction and operation will definitely appear from the 30 detailed description to follow.

I accomplish the objects of my invention by the means described in the following specification. The invention is clearly defined and pointed out in the claims.

35 A structure constituting a preferred embodiment of my invention is illustrated in the accompanying drawings forming a part of this specification, in which:

40 Figure 1 is an elevation of my improved display box looking upon the face thereof and assuming the same to be lying flat on its bottom in a showcase or similar exhibiting device.

Fig. 2 is a side elevation illustrating that 45 my device is susceptible of display in an oblique or tilting position.

Fig. 3 is a central longitudinal horizontal section illustrating the interdependency between the box itself, certain partitions and 50 the individual holders.

Fig. 4 is a perspective view of one of the holders removed from the box.

55 Fig. 5 is a fragmentary perspective view of the upper right-hand corner of my improved display box depicting my unique

method of presenting means for printing or other words of description thereon and my method of retaining certain of the holders in display position during the removal of a companion holder; and,

60 Fig. 6 is a sectional detail showing the parts in Fig. 5 in assembled position.

In the drawings, similar reference characters refer to similar parts throughout the several views.

65 Referring now in detail to the accompanying drawings, my improved display box comprises a rear wall 10, top and bottom walls 11 and 12 respectively and end walls 13 and 14.

70 An inspection of Figs. 1 and 3 of the drawings will show that the box is indeed relatively shallow as distinguished from the usual type of article used for the display of similar merchandise.

75 My invention has been especially directed to a device for holding garters, preferably the present-day garters as worn by young ladies and others. Obviously, the display of such articles assists materially in the sale thereof, provided said articles are presented as worn, and to this end I have devised the holders 15, having their frontal portions bowed or arcuately formed, as indicated at 16, while the rear portions, or perhaps the basal portions are flattened as indicated at 17 to lie against the rear wall 10 of the box as indicated in Fig. 3.

80 Figure 1 of the drawings pictorially shows a pair of garters arranged around a 85 holder 15 and it will be observed that the herein presentation is similar to the appearance assumed by the garters when arranged in the customary manner. Thus, my improved holder is peculiarly adapted to display a portion of the garter, as above described, and yet confine the same to a relatively small space, that is, a shallow box. This is a feature of some importance.

85 While the drawings disclose the operation of but one of the holders, it will, of course, be understood that each thereof is provided with a pair of garters arranged preferably in tiers, each tier being separated by a horizontal partition 18.

90 In order to display the box in a position as best practice appears feasible, I have provided the rear thereof with an easel-structure 19, which is adapted to be folded flush with the rear of said box, thereby permitting 95 100 105 110

the latter to assume a horizontal position (see Fig. 1), for display on a shelf within a showcase or on the top thereof.

Adjacent the top wall 11 I have positioned a unique structure which presents a front portion 20, flush with the contiguous walls of the device, upon which may be suitably printed the manufacturer's name, or other display, such as trade-marks, or the like. This structure also performs a new and novel function in that it serves to exert a slight wedging action to the upper tier of holders which, of course, is communicated to each tier positioned below the same.

Attention is directed to Figs. 5 and 6 of the drawings wherein it will be noted that the front portion 20 extends beneath the top wall 11 and is secured thereto by any improved fastening means 21. Said front portion also extends forwardly and presents a foldable portion 22, being scored as indicated at 23. Further, I provide said front portion 20 with a side extension 24, scored at 25. Prior to the folding operations the structure assumes the position denoted in Fig. 5 and in shaping said structure to the desired form, said portion 24 is folded at 25 and inserted within the side wall 14, whereupon the portion 22 is folded at 23 and the whole structure inserted within the box as shown in Fig. 6. Said portion 22 now bears upon the top edges of the holders 14, as shown, and it is quite evident that the slight wedging action exerted upon the latter prevents the displacement of a holder when its companion is removed for inspection and subsequent purchase of the garters.

My improved holder 15 is preferably made from a single strip of material, shaped according to Fig. 4, the free ends thereof being overlapped and secured in any approved manner, or said ends may be slightly beveled and secured by an adhesive so as to present unrestricted plane side portions.

In accordance with the patent statutes, I have illustrated my invention in concrete

form and as constructed in a specified manner, but it will be distinctly understood that I do not propose to limit myself to the precise structural details set forth, since various modifications will immediately suggest themselves to those skilled in the art without departing from the spirit of my invention, the scope of which is set forth in the following claims.

Having thus described my invention, I claim as new and desire to secure by Letters Patent:

1. A display device comprising an open front box-like structure, a plurality of article holders arranged in tiers therein, each holder being formed from an integral blank semi-circular in cross-section and presenting its bowed frontal portion forwardly of the structure and extending beyond the plane of the front edge thereof, horizontal partitions arranged between each tier of article holders and having their front edges terminating flush with said bowed portion of said holders and foldable means positioned at the top of said box-like structure adapted to exert a wedging action to the various tiers of holders for the purpose specified.

2. A display device comprising an open front box-like structure, a plurality of article holders detachably mounted in tiers within said structure, each holder being formed from an integral blank and formed to present a bowed frontal portion extending beyond the plane of the face of said box-like structure, while the flat base thereof abuts the rear of said structure, horizontal partitions arranged between each tier of article holders and having their front edges terminating flush with the bowed portions of said holders, and foldable means positioned at the top of said box-like structure having a depending flap adapted to press upon the upper tier of holders and communicate a wedging action to each tier positioned below.

In testimony whereof I affix my signature.

BARNEY SEAMAN.
